ELECTRICAL CONNECTION MEANS

Harry A. Douglas, Bronson, Mich., assignor to
 Kingston Products Corporation, a corporation
 of Indiana

Application June 10, 1935, Serial No. 25,715

12 Claims. (Cl. 173—328)

My invention relates to electrical connection means and may be embodied in terminal posts adapted for the reception of conductor terminals. In its more specific aspects my invention relates to terminal posts mounted or mountable on a support, and more particularly to terminal posts adapted for the reception of plug conductor terminals of the snap type. The principal object of my invention is to provide new and improved electrical connection means of these types. In the drawing accompanying this specification and forming a part of this application, I have shown for purposes of illustration, several forms which my invention may assume, and 15 in this drawing:

Figure 1 is a perspective view of a terminal post mounted on a base, embodying my invention.

Figure 2 is a vertical sectional view of the construction shown in Figure 1, enlarged, the section being taken transverse to the longitudinal extent of the base. Figure 2 also includes, in addition, a plug conductor terminal of the snap type cooperable with the terminal post,

Figure 3 is a perspective view of the terminal post shown in Figure 1, viewed from a different angle, and before the post is assembled with one of the elements of the base, the element of the base with which the post is to be assembled being fragmentarily shown in perspective,

Figure 4 is a section on the line 4—4 of Figure 2, looking in the direction of the arrows,

Figure 5 is a perspective view analogous to Figure 3, but showing another embodiment of my invention, and

Figure 6 is a sectional view, analogous to Figure 4, but embodying the corresponding elements of Figure 5.

Referring to the embodiment of my invention illustrated in Figures 1 through 4, a terminal post 10 is mounted on a base 11. The terminal post is here shown as having a solid metallic body portion 12 of generally oblong rectangular cross-section, having oppositely disposed longitudinally extending wider faces 13, 14 and opposite longitudinally extending narrower faces 15, 16 at right angles to the faces 13, 14. The body portion 12 is here shown as provided with two plug conductor terminal receiving transverse apertures 17, 18, which may be formed by drilling through the body 12 from one of the wider faces 13, 14 through the other. The upper end of the terminal post 10, as viewed in Figures 1 and 2, is frusto-conical and is provided with a chamber 19 adapted to receive a detent means 20.

The chamber 19, proper, may be formed by a longitudinal bore 21 which is put into communication with the upper transverse aperture 17 by means of a communicating bore 22 of lesser diameter than the bore 21 of the chamber proper. 5

The detent means 20 is here shown as comprising a generally hemispherical portion 23 adapted to extend freely through the communicating bore 22 into the transverse aperture 17. The detent means 20 is provided with an annular flange 10 24 adapted to be seated on a shoulder 25 formed at the end of the bore 21. The detent means 20 is biased to the position shown in Figure 2 by means of a helical spring 26, disposed in the bore 21, one end of which bears against the annular flange 24 and the other end of which bears against an abutment 27 formed, in this instance, by closing inwardly the metal surrounding the upper end of the bore 21 of the chamber 19. The detent means 20 is here shown as 20 including an integral shank 28 disposed within the helical spring 26 and serving to guide the detent means 20 for longitudinal movement in cooperation with the spring 26 and the bore 21. The lower end of the terminal post 10 is also 25 provided with a chamber 29, similar to the chamber 19, adapted to receive detent means 30, the upper end of the chamber 29 being in communication with the lower transverse aperture 18 through a communicating bore 31, similar to the 30 bore 22. The detent means 30 is shown as identical with the upper detent means 20, except, of course, that the hemispherical portion of the lower detent means 30 extends upwardly into the lower transverse aperture 18. 35

The lower detent chamber 29 may be formed by drilling a longitudinal bore 32 into the lower end of the body portion 12 of the terminal post 10. The lower end of the post 10 has its four corners 33 rounded off concentric with the bore 40 32. The diameter of the cylindrical surface defined by the rounded corners 33 is in this instance somewhat greater than the distance between the wider opposite sides 13, 14 of the body portion 12, thereby leaving flat surfaces 34, 35, 45 and forming four shoulders 36. Oppositely disposed longitudinally extending tongues 37, 38 are here shown as formed by cutting a slot 39 diametrically across the lower end of the body portion, the slot extending axially from the lower 50 end of the post to the shoulders 36 and transversely across the body portion parallel to the wider faces 13, 14 of the body portion 12. The slot 39 is here shown as of somewhat less width than the diameter of the longitudinal bore 32. 55

thereby leaving arcuate portions 40, 41 of the bore 32 on the radially inner surfaces of the tongues 37, 38. The ends of the tongues may have their outer edges 42, 43 beveled off to form 5 fragmentary generally conical surfaces, concentric with the bore 32.

The tongues 37, 38 are adapted to be disposed through a non-circular aperture 44 in a plate 45, here shown as of insulating material. The 10 aperture 44 in the plate 45 has diametrically opposite segmental parts 45, 46 of arcuate outline, the circle defined by these segmental parts 45, 46 desirably being of a diameter such as to snugly fit the arcuate surfaces of the corners 15 33 of the tongues 37, 38. The aperture 44 in the plate 45 is desirably provided with diametrically opposite radially inwardly extending projections 47, 48 having arcuate radially inner ends, the width of the projections 47, 48 being such 20 that these projections are adapted to be disposed between the inner flat face portions of the tongues 37, 38 formed by the slot 39.

In assembling the terminal post 10 with the plate 45, the tongues 37, 38 are inserted into 25 the segmental parts 45, 46 of the aperture 44 in the plate 45, the projections 47, 48 and also the shoulders 38 limiting the insertion of the tongues through the aperture. The ends of the tongues 37, 38 are then spread radially outwardly, 30 as by bending, pressing, spinning, or in any other suitable manner, until the spread portions form feet 49, 50, the tops of which are in tight contact with the under surface of the plate 45, as viewed in Figure 2, thereby tightly mounting 35 the post 10 on the plate 45. The feet 49, 50 may be worked to arcuate form, concentric with the bore 32, as may be seen in Figure 4.

When the post 10 has been mounted on the plate 45, the detent means 30 and a spring 51, 40 similar to the spring 26, may then be inserted in the detent chamber 29. Then the post 10 and the plate 45, to which the post is attached, may be assembled with another plate 52, here shown as of insulating material, the bottoms of the 45 feet 49, 50 abutting the plate 52. The plates 45, 52 may be held together in any suitable manner, these plates being here shown as disposed in a channel 53, the sides of which are provided with fingers 54 clinched over the top of the upper 50 plate 45, thereby tightly holding the plates 45, 52 together.

It will be evident that the plate 52 serves as an abutment for the lower end of the spring 51.

The composite base 11 formed by the plates 55 55 45, 52 and by the channel 53 may be fastened to a support in any suitable manner, as for example by providing apertures 55, 56 extending through the components of the base, through which apertures 55, 56 fastening means (not 60 shown) may be disposed.

If desired, spacing means (not shown) may be provided in spaces 57 between the plates 45, 52.

In Figure 2 is shown a plug conductor terminal 58, cooperable with the terminal post 10, the plug conductor terminal including a generally cylindrical portion 59 provided with an annular furrow 60, the end 61 of the plug being frustro-conical. The plug terminal 58 may be 70 fastened to a conductor 62 disposed therein by swaging, as indicated by swedge indentations 63. When the plug conductor terminal 58 is inserted into, for example, the transverse aperture 17, the frustro-conical end 61 serves to 75 cam the detent means 20 upwardly, further in-

serting movement causing the hemispherical portion 23 of the detent means 20 to snap into the annular furrow 60. It will of course be evident that the plug conductor terminal 58 is cooperable with either one of the apertures 17, 18, or both apertures concurrently may receive such plug conductor terminals.

While but one terminal post 10 has been shown mounted on the base 11, it will be apparent that as many terminal posts as may be desired may be mounted on a single base.

Referring to the embodiment shown in Figures 5 and 6, a terminal post 64 is here shown, which, with the exception of the formation of the tongues formed at the lower end of the post, is similar in all respects to the terminal post 10. In the embodiment of Figure 5 the lower end of the post 64 is provided with a longitudinal bore 65 forming a detent chamber 66, similar to the detent chamber 29 of the post 10. Two oppositely disposed longitudinally extending tongues 67, 68 are formed by cutting two diametrically opposite recesses 69, 70 into opposite faces 71, 72 on the post, these recesses 69, 70 extending from the lower end of the post and forming transverse shoulders 73, 74. The recesses 69, 70 are of a radial depth such that diametrically opposite segmental portions of the surfaces of the bore 65 are removed, leaving diametrically opposite segmental portions 75, 76 of the surface of the bore 65, forming the radially inner surfaces of the tongues 67, 68, the tongues 67, 68 being then, in this instance, of a width less than the diameter of the bore 65.

The tongues 67, 68 are adapted to be inserted in an aperture 77 in a plate 78, here shown as of insulating material, corresponding to the plate 45 of Figures 1 through 4. The aperture 77 in this instance is such as to generally outline the tongues 67, 68 and is therefore of generally rectangular oblong shape, the narrower sides 79 being such as to fit the width of the tongues 67, 68 and the longer sides 80 being approximately the same length as the distance between the radially outer faces of the tongues 67, 68. In the present instance the proportion of the parts is such that the longer opposite sides 80 of the aperture 77 are desirably provided with cut-out portions or arcuate recesses 81 conforming generally to the longitudinal bore 65.

In assembling the post 64 with the plate 78, the tongues 67, 68 are inserted through the aperture 77, the shoulders 73, 74 of course limiting the inserting movement. The tongues 67, 68 are then spread or bent radially outwardly in any suitable manner so as to form feet 82, 83, the upper portions of which bear tightly against the lower surface of the plate 78. The section shown in Figure 6 is analogous to the section shown in Figure 4, and shows the appearance of the 60 tongues 67, 68 after they have been bent or otherwise spread against the bottom of the plate 78 to form the feet 82, 83.

The post 64 of the embodiment of Figures 5 and 6, after it has been fastened to the plate 78, 65 may of course have detent means 84 and a spring 85, similar to the detent means 30 and spring 51 of the embodiment of Figures 1 through 4, inserted in the detent chamber 66, the parts so assembled being then mounted on a plate (not 70 shown), similar to the plate 52, and the plate 78, and the plate similar to the plate 52, held together by a channel 86.

It will be evident that the post 64 is adapted for the reception of a plug conductor terminal, 75

such as 58, in either one or both of its conductor terminal receiving apertures in a manner already described in connection with the post 10.

In both of the embodiments of my invention herein illustrated the feet formed by the ends of the tongues extend in a general direction away from those faces of the posts through which the plug conductor terminals are insertable, thereby better holding the posts with respect to their bases.

From the foregoing it will be apparent to those skilled in the art that the illustrated embodiments of my invention provide new and improved electrical connection means, readily and conveniently constructed, assembled, and mounted on a support and accordingly, accomplish at least the principal object of my invention. On the other hand, it also will be obvious to those skilled in the art that the illustrated embodiments of my invention each may be variously changed and modified, or features thereof, singly or collectively, embodied in other combinations than those illustrated, without departing from the spirit of my invention, or sacrificing all of the advantages thereof, and that accordingly, the disclosure herein is illustrative only, and my invention is not limited thereto.

I claim:

1. In combination: a metallic terminal post having a solid body portion provided with an aperture for receiving a conductor terminal and also formed with a longitudinal bore entering said body portion at one end; detent means disposed within said bore and cooperable with said body portion aperture; spring means disposed in said bore and operable to urge said detent means to operative position; said body portion at said end having opposite surfaces formed of a width substantially equal to the diameter of said longitudinal bore, forming a plurality of tongues; and a support, having an aperture circumscribing the outer transverse margins of said tongues, and being formed with cut-out portions in the margins thereof to provide for passage of said detent means and said spring means; and each tongue having the free end thereof bent to overlie said support to hold said post to said support.

2. In combination: a support, having an aperture, and provided with portions projecting inwardly from the margin of said aperture; a terminal post, provided with an aperture for receiving a conductor terminal, and having a slotted part forming a plurality of tongues constructed and arranged to pass through said support aperture, the slots between said tongues fitting the projections on the margin of said support aperture to prevent relative movement of said post with respect to said support, and the free end of each tongue being bent to overlie said support to hold said post to said support; and resilient means extending through said support aperture and cooperable with said post aperture, for yieldably engaging and holding a conductor terminal disposed in said post aperture.

3. In combination: a support, having an aperture; a terminal post, provided with an aperture for receiving a conductor terminal, and a longitudinal bore entering said post at one end, said post also having abutment means spaced inwardly from said end, the part of said post margining said bore being disposed through said support aperture to an extent limited by engagement of said abutment means with one surface of said support, said end of said post being formed to overlie the other surface of said support to hold

said post to said support; an abutting member connected to said support; and biasing means interposed between a surface of said abutting member and said post aperture, operable to yieldably engage and hold a conductor terminal disposed in said aperture.

4. In combination: a support, having an aperture; conductor terminal receiving means, having an aperture for receiving a conductor terminal, and a recess entering one end of said receiving means and communicating with said aperture; said receiving means having a part of reduced size margining said recess and forming a shoulder with the remaining part of said receiving means, said reduced part being adapted to pass through said support aperture with said shoulder abutting one surface of said support and the extremity of said part being bent to overlie the opposite surface; a member abutting said opposite surface of said support, said member spanning said extremity and closing off the open end of the recess in said receiving means; detent means, disposed in said recess, and bearing against said member, said detent means extending into said receiving means aperture and being operable to engage a conductor terminal disposed in said aperture; and fastening means, constructed and arranged to hold said member assembled with said support.

5. In combination: a support, having an aperture; a terminal post of polygonal cross-section, the corners of said post being chamfered inwardly from one end to form shoulders, said post having a bore extending inwardly from said one end, and a transverse bore communicating with said first bore and adapted to receive a conductor terminal, said end of said post being slotted to form tongues; said shoulders abutting one surface of said support, and said tongues extending through said support aperture and having their extremity bent to overlie the opposite surface of said support; and biasing means, disposed in said first bore, for cooperation with a conductor terminal in said transverse bore.

6. In combination: a support, having an aperture; a terminal post, having at least an end portion of polygonal cross-section, at least certain of the corners of said portion being chamfered a predetermined distance inwardly from the extremity of said portion to form shoulders, said end portion being furcated to form tongue means; said tongue means extending through said support aperture a distance limited by abutment of said shoulders with one surface of said support, the free end of said tongue means being bent to overlie the opposite surface of said support, holding said post against axial movement, and said tongue means engaging portions of the defining surface of said support aperture, holding said post against rotation.

7. In combination: a support, having an aperture the margin of which is formed with a plurality of spaced-apart recesses; a terminal post, of polygonal cross-section, the corners of said post being chamfered a predetermined distance inwardly from one end to form shoulders, said end being furcated to form a plurality of tongues spaced-apart a distance corresponding to the spacing of said recesses; said tongues extending through respective recesses a distance limited by abutment of said shoulders with one surface of said support, the extremity of each of said tongues being bent to overlie the opposite surface of said support, holding said post against axial movement, and each of said tongues engaging margins

of respective recesses, holding said post against rotation.

8. In combination: a support, having an aperture the margins of which are formed with a plurality of spaced-apart recesses; a terminal post, of polygonal cross-section, having a transverse aperture for receiving a conductor terminal, and a longitudinal aperture extending inwardly from one end of said post and communicating with said transverse aperture, the corners of said post being chamfered a predetermined distance inwardly from said one end to form shoulders, said one end being furcated to form a plurality of tongues spaced apart a distance corresponding to the spacing of said recesses; said tongues extending through respective recesses a distance limited by abutment of said shoulders with one surface of said support, the extremity of each of said tongues being bent to overlie the opposite surface of said support, holding said post against axial movement, but permitting access to said longitudinal aperture from said opposite surface of said support, and each of said tongues engaging margins of respective recesses, holding said post against rotation; a member, held in position overlying said opposite surface of said support, closing off access to said longitudinal aperture; and biasing means, extending through said longitudinal aperture, having one end bearing against said member, and its other end in position to yieldably engage a conductor terminal disposed in said transverse aperture.

9. In combination: a metallic terminal post having a solid body portion provided with an aperture for receiving a conductor terminal and also formed with a longitudinal recess entering said body portion at one end; detent means disposed within said recess and cooperable with said body portion aperture; resilient means disposed in said recess and operable to urge said detent means to operative position; said body portion at said end having opposite surfaces formed of a width substantially equal to the diameter of said longitudinal recess, forming a plurality of tongues; and a support, having an aperture circumscribing the outer transverse margins of said tongues, and being formed with cut-out portions in the margins thereof to provide for passage of said detent means and said resilient means; and each tongue having the free end thereof distorted outwardly whereby to hold said post to said support.

10. In combination: a support, having an aperture; projections provided on said support ex-

tending inwardly from the margin of said aperture; a terminal post having a body portion provided with an aperture for receiving a conductor, said body portion having bifurcations constructed and arranged to pass through said support aperture, the openings between said bifurcations fitting said projections to prevent relative movement of said post with respect to said support, and the free end of each bifurcation being distorted to overlie said support to hold said post to said support; and resilient means extending through said support aperture and cooperable with said post aperture for yieldably engaging and holding a conductor disposed in said post aperture.

11. In combination: a support, having an aperture, and provided with portions projecting inwardly from the margin of said aperture; a terminal post having a body portion provided with an aperture for receiving a conductor terminal, said body portion having bifurcations constructed and arranged to pass through said support aperture, the openings between said bifurcations fitting the projections on the margin of said support aperture to prevent relative movement of said post with respect to said support, and the free end of each bifurcation being bent to overlie said support to hold said post to said support; resilient means extending through said support aperture and cooperable with said post aperture, and yieldably engaging and holding a conductor terminal disposed in said post aperture; and means for abutting and holding said resilient means in place.

12. In combination: a support, having an aperture; a terminal post having a body portion provided with an aperture for receiving a conductor terminal, and a longitudinal recess entering said body portion at one end, said post also having abutment means spaced inwardly from said end, the part of said post margining said recess being disposed through said support aperture to an extent limited by engagement of said abutment means with one surface of said support, said end of said post being formed to overlie the other surface of said support to hold said post to said support; an abutting member connected to said support; biasing means interposed between a surface of said abutting member and said post aperture, operable to yieldably engage and hold a conductor terminal disposed in said aperture; and fastening means, constructed and arranged to hold said member in assembly with said support.

HARRY A. DOUGLAS.
